UNITED STATES PATENT OFFICE.

HAROLD G. WARR, OF PARK RIDGE, ILLINOIS, ASSIGNEE TO THE P & M COMPANY, OF CHICAGO, ILLINOIS, A CORPORATION OF ILLINOIS.

RAIL ANCHOR.

Application filed December 1, 1924. Serial No. 753,257.

To all whom it may concern:

Be it known that I, HAROLD G. WARR, a citizen of the United States, residing at Park Ridge, in the county of Cook and State of Illinois, have invented certain new and useful Improvements in Rail Anchors, of which the following is a specification.

My invention relates to rail anchoring devices of the general type adapted to grip the base portion of a railroad rail and has for its principal object the provision of a new and improved device of the above character which will be easy of application, reliable in its operation, and which will be inexpensive to manufacture.

A more specific object of the invention is to provide an improved anchor device comprising a rail gripping member and a separately formed member for retaining the rail gripping member in its operative position on a rail, which members are preferably so constructed that they may be permanently assembled at the factory before shipment and be applied to a rail while they are in their normal assembled condition.

Another object of the invention is to provide an improved anchor device comprising a rail gripping member and a separately formed member for retaining the rail gripping member in its operative position on a rail, which members are so formed that the rail gripping member may be made of a uniform size to fit rails having base flanges of different thickness and so that the variations in the dimensions of the anchor necessary to accommodate rails having base flanges of different widths may be accomplished by varying the length of the retaining member, or by varying its assembled position with relation to the other member.

The invention has for further objects the novel arrangements, constructions and combinations of parts hereinafter described and claimed for carrying out the above stated objects and such other incidental objects as will appear from the following description of the invention.

The invention is illustrated in certain preferred embodiments in the accompanying drawing, wherein:

Fig. 1 is a plan view of a rail anchor constructed in accordance with my invention applied to the base portion of a railroad rail.

Fig. 2 is a face view of the anchor con-

struction shown in Fig. 1, the base portion of the rail being shown in section and the normal position of the jaw member when the anchor is free of the rail being shown in dotted lines.

Fig. 3 is a view in perspective of the rail gripping member of the anchor construction shown in Figs. 1 and 2.

Fig. 4 is a fragmentary face view of a modified construction, and

Fig. 5 is a view in perspective of the rail anchor shown in Fig. 4.

The invention is illustrated in Figs. 1, 2 and 3 of the drawing as consisting of a rail gripping member 10 adapted to fit over one edge of the base portion of a railroad rail 11, and a retaining member 12 engaged with the rail gripping member and adapted to snap over the opposite edge of the rail base to hold the gripping member 10 in its operative position.

The gripping member 10 is preferably formed from a sheet steel blank, the body portion 13 of which is bent along the horizontal line to provide a jaw 14 for engaging the upper inclined surface of the rail base. The end portions 15, 15^a of the blank are bent at right angles to the body so as to provide vertically disposed flanges for engaging the bottom surface of the rail base. The extremity 16 of the flange 15 is preferably bent to a position parallel to the body 13 and is pierced preferably with a square opening 17 which aligns with a similar opening 18 in the body portion 13. The jaw portion 14 is bent to such position that the distance between the lower surface of the jaw and the upper edges of the flanges 15 and 15^a will normally be less than the thickness of the rail base when the device is free of the rail so that it will be necessary, when driving the member 10 to its rail gripping position, to distort the jaw 14 from the dotted line position to the full line position shown in Fig. 2, thereby insuring a firm grip of the anchor on the rail and also making it practicable to apply the member 10 to rail bases of different thickness.

The retaining member 12 consists of a metal bar, preferably square in cross section and made of spring metal, one end of which extends through the openings 17 and 18 of the member 10 and is provided with a down-turned portion 19 adapted to bear against the outer face of the member 10. The other

end of the retaining member is bent upwardly at 20 to provide a portion 21 for bearing against the bottom surface of the rail base and is formed with an upturned 5 portion 22 adapted to engage with the vertical surface of the rail base at a point opposite to the rail gripping member.

It will be seen that the members 10 and 12, being formed separately, may be made 10 of metals of different quality and in other respects contain the various manufacturing advantages present in a two-piece anchor. The separately formed members, however, are preferably permanently connected at the 15 factory so that the anchor may be shipped and applied to a rail as a one piece anchor.

In applying the anchor to a rail, the jaw 14 is hooked over one edge of the rail base with one of the vertical flanges 15 or 15^a 20 in a position to bear against a cross tie 23. The member 10 is then driven into tight gripping engagement with the rail base. If desired, the member 10 and the retaining member 12 may be driven simultaneously to 25 their operative positions by striking the end 19 of the retaining member. When the members 10 and 12 are driven to their applied position in the above manner, the end 22 of the member 12 will snap into engagement 30 with the opposite edge of the rail base when the member 10 reaches its fully applied position and thereby hold the gripping member from backing off the rail. The members 10 and 12 may also be applied by 35 first driving the member 10 to its applied position and then driving the member 12 transversely of the rail until the end 22 of said member snaps over the opposite edge of the rail base. The retaining member is 40 not ordinarily subjected to any appreciable stress resulting from the creeping of the rail and therefore may be made relatively light in weight. The anchor may be made for rails having base flanges of different widths 45 by simply varying the length of the retaining member. It will also be seen that the retaining member being relatively light may be easily flexed to permit the removal and the reapplication of the anchor when occasion requires without danger of subjecting 50 the anchor to excessive distortion.

In Figs. 4 and 5 I have illustrated a modified construction in which the rail gripping member 10^a is made of cast metal instead 55 of sheet steel, as described in connection with the preceding figures. The member 10^a is preferably provided with relatively heavy upper and lower jaws 24 and 25, the inner surfaces of which define a recess 26 60 for receiving one edge of the rail base.

This recess is normally smaller than the thickness of the rail base so that the jaw 24 will be slightly distorted, substantially as shown in dotted lines in Fig. 4, when the 65 member is driven to its applied position.

27 designates a tie abutting foot and 28—28 reinforcing webs. The retaining member 12^a may be the same in construction as the member 12 described in connection with Figs. 1 and 2 with the exception that the 70 member 12^a may be made shorter than the member 12 and the portion 19^a is relatively short and preferably formed by an upsetting operation instead of bending the bar as shown in Fig. 2. It will be obvious, however, that the downwardly projecting portion 19 of Fig. 2 may likewise be formed by 75 upsetting the end of the bar.

The member 12^a is secured rigidly to the rail gripping member by casting the member 80 10^a around the upset end 19^a of the retaining member so as to imbed the end 19^a in the metal of the member 10^a. This result may be accomplished by so positioning the end 85 of member 12^a in the mold in which the casting is formed, that the molten metal, when poured into the mold, will flow around the end of the member 12^a. With the cast metal construction as above described, anchors may 90 be formed to fit rail bases of different widths 95 by simply shifting the position of the member 12^a in the mold, in which the casting 10^a is formed, so as to provide the desired distance between the shoulder 29^a of member 12^a and end wall 30 of the recess 26 of the 100 cast member 10^a.

While I have described my invention in two specific embodiments, it will be obvious that other modifications in structure might be made without departure from the spirit of my invention. I therefore wish it understood that I contemplate all such changes in structure as come within the scope of the appended claims.

I claim:

1. A rail anchor comprising a rail base engaging member adapted to be driven into engagement with one flange of the rail base and means for retaining said base engaging member in its operative position comprising a spring member adapted to snap over the opposite edge of the rail base.

2. A rail anchor comprising a rail base engaging member adapted to be driven into engagement with one flange of the rail base and means for retaining said rail base engaging member in its operative position comprising a separately formed spring member attached to said rail engaging member and adapted to snap over the opposite edge of the rail base.

3. A rail anchor comprising a rail base engaging member adapted to be driven into engagement with one flange of the rail base, and means for retaining said rail base engaging member in its operative position comprising a separately formed spring member normally permanently attached to said rail engaging member and adapted to snap over the opposite edge of the rail base.

4. A rail anchor comprising a rail base engaging member adapted to be driven into engagement with one flange of the rail base and means for retaining said rail base engaging member in its operative position comprising a separately formed member normally attached permanently to said rail engaging member and adapted to bear against the opposite edge of the rail base. 70
5. A rail anchor comprising a rail base engaging member adapted to be driven into engagement with one flange of the rail base and means for retaining said rail base engaging member in its operative position comprising a bar normally attached permanently to said rail engaging member and adapted to engage the opposite edge of the rail base when said first named member is in its operative position. 75
6. A rail anchor comprising a rail base engaging member adapted to be driven into engagement with one flange of the rail base and means for retaining said rail base engaging member in its operative position comprising a separately formed member normally attached permanently to said rail engaging member and adapted to bear against the opposite edge of the rail base; said rail engaging member being provided with jaw portions so disposed with relation to each other as to be spread apart during the application of said member to its operative position. 80
7. A rail anchor comprising a jaw member adapted to be applied to one flange of a rail base and to be distorted during its application to a rail, and a separately formed member having a snap engagement with the opposite edge of the rail base for retaining said jaw member on the rail. 85
8. A rail anchor comprising a jaw member adapted to be applied to one flange of a rail base and to be distorted during its application to a rail, and a separately formed spring bar secured to the jaw member and having a snap engagement with the opposite edge of the rail base for retaining said jaw member on the rail. 90
9. A rail anchor comprising a rail gripping member adapted to be applied to one edge of a rail base, and a separately formed retaining member for holding the gripping member in its applied position; said retaining member comprising a bar formed at one end with an angularly disposed portion for engaging the edge of the rail base and provided at the other end with a portion bent over a part of said gripping member to attach said members together. 95
10. A rail anchor comprising a rail gripping member and a retaining member for holding the gripping member in its applied position; said gripping member being provided with upper and lower jaws for engaging the upper and lower surfaces of a rail 100
- base at one side of the rail and provided with an opening below the rail base to receive said retaining member, and said retaining member being adapted to be driven from the side of the rail engaged by said gripping member into engagement with the opposite edge of the rail base. 105
11. A rail anchor comprising a rail gripping member and a retaining member attached to the gripping member and adapted to hold it in its applied position; said gripping member being provided with a jaw for bearing against the upper surface of the rail base and with a vertically disposed flange providing a jaw for engaging the bottom surface of the rail base, and said retaining member being adapted to be driven from the side of the rail engaged by said gripping member into engagement with the opposite edge of the rail base. 110
12. A rail anchor comprising a rail gripping member and a retaining member for holding the gripping member in its applied position; said gripping member being provided with a jaw for bearing against the upper surface of the rail base and with spaced vertically disposed flanges for engaging the bottom surface of the rail and said retaining member comprising a spring bar attached to said gripping member and having a snap engagement with the opposite edge of the rail base. 115
13. A rail anchor comprising a rail gripping member formed with a jaw for engaging the upper surface of a rail base at one side of a rail and with vertically disposed flanges extending transversely of the rail and adapted to bear against the bottom surface thereof, and means for retaining said gripping member in operative position comprising a spring bar attached to the gripping member and adapted to be driven from the side of the rail engaged by said gripping member into engagement with the opposite edge of the rail base. 120
14. A rail anchor comprising a rail gripping member formed with a jaw for engaging the upper surface of a rail base at one side of a rail and with vertically disposed flanges extending transversely of the rail and adapted to bear against the bottom surface thereof, and means for retaining said gripping member in operative position comprising a spring bar attached to the gripping member and engaging the opposite edge of the rail base; the body portion of said gripping member being formed with an opening to receive one end of said retaining member and one of said flanges being formed to provide a support for said retaining member. 125
15. A rail anchor comprising a rail gripping member formed with a jaw for engaging the upper surface of a rail base at one side of a rail and with vertically disposed 130

- 4
- flanges extending transversely of the rail and adapted to bear against the bottom surface thereof, and means for retaining said gripping member in operative position comprising a spring bar attached to the gripping member and engaging the opposite edge of the rail base; the body portion of said gripping member being provided with an opening to receive one end of said retaining member and the extremity of one of said flanges being bent to a position parallel to the body and provided with an opening to receive one end of said retaining member. 16. A rail anchor comprising a rail gripping member formed from a sheet metal blank bent to provide jaws for engaging the upper and lower surfaces of a rail base, and a retaining member comprising a bar attached to the said gripping member and provided at one end with an upstanding portion adapted to snap over one edge of the rail base. 15 20

HAROLD G. WARR.
